Primary Examiner — Jonathan J Han(74) *Attorney, Agent, or Firm* — Cowan, Liebowitz & Latman, P.C.(57) **CLAIM**

The ornamental design for a jean shoe, as shown and described.

DESCRIPTION

FIG. 1 is a perspective view of the jean shoe of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another perspective view thereof; and,

FIG. 9 is a further perspective view showing the jean shoe in an open configuration.

The broken lines in the drawings, including broken lines that represent stitching, illustrate features of the jean shoe that form no part of the claimed design. The broken line boundary line within the upper opening of the jean shoe in FIG. 6 show the bounds of the claimed design, and the area within the boundary a long with the boundary line form no part thereof.
